UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

BUCKET-DOOR-OPENING MECHANISM.

1,415,291.

Specification of Letters Patent.

Patented May 9, 1922.

Application filed March 26, 1921. Serial No. 455,903.

To all whom it may concern:

Be it known that I, FRANKLIN E. ARNDT, a citizen of the United States, residing at Galion, in the county of Crawford and State 5 of Ohio, have invented certain new and useful Improvements in Bucket-Door-Opening Mechanisms, of which the following is a specification.

This invention relates to means for transporting materials, such as coal, ballast and the like, and particularly to that form of transporting apparatus in which a carrier is used and a bucket mounted upon the carrier for travelling movement therewith and 15 adapted to be raised or lowered toward or from the carrier.

Such buckets as these are provided with means whereby the doors which form the bottom of the bucket may be caused to open 20 when the bucket has lowered into proximity to the point where the material is to be dumped and whereby the doors are closed when the bucket is raised into proximity to the carrier.

25 The general object of my invention is to provide means for automatically opening the doors of the bucket when the bucket moves into proximity with the dump, and particularly to provide means which, on contact 30 with the material on the dump or with the ground, will cause the automatic release of said doors, permitting the doors to open to discharge the contents of the bucket.

Other objects have to do with the details 35 of construction and arrangement of parts as will appear more fully hereinafter.

My invention is illustrated in the accompanying drawings, wherein:—

Figure 1 is a side elevation of a hoisting bucket, carrier and supporting rail constructed in accordance with my invention;

Figure 2 is an end elevation of the structure shown in Figure 1, the supporting rail being in section;

45 Figure 3 is a fragmentary sectional view through the lower portion of the bucket, the section being taken parallel to the end walls of the bucket and showing the door closed;

50 Figure 4 is a fragmentary sectional view on the same plane as Figure 3, showing the door open;

Figure 5 is an elevation of the door releasing mechanism showing the door in section;

55 Referring to these drawings, 10 designates

a rail forming part of a supporting structure, such as is illustrated and described in my Patent #1,406,327, dated February 14, 1922, and co-pending herewith. This rail or supporting beam is in the form of 60 an I-beam. Operating upon this rail and supported thereby is a carrier, designated generally 11, this carrier being formed essentially of two plates 12 disposed on each side of the I-beam 10 and embracing this I-beam, 65 the upper corners of these plates carrying the supporting wheels 13 which bear upon the base flanges of the I-beam. Having bearing engagement in the lower corners of the plates 12 are the transverse shafts 14 70 supporting the grooved wheels 15. Passing over these grooved wheels is a cable 16 which between the wheels forms a bight.

The bucket, which is designated generally 17, has the usual form, the bottom of the 75 bucket body being open, this open bottom being normally closed by two downwardly inclined doors 18 hinged at 19 to the side walls of the bucket body. Disposed above the bucket body and extending parallel to 80 the side walls thereof and above the middle of the bucket body are a pair of parallel channel irons 20. These channel irons are connected to each other in any suitable manner, and riveted, bolted or otherwise attached to the ends of the channel irons are the downwardly extending hangers 21. These hangers at their lower ends are formed with bearings for trunnion pins 22 which are attached in any suitable manner to the ends 90 of the bucket and project outward and pass through the irons in the lower ends of the hangers. Thus the bucket is pivotally supported. A collar 23 is also supported upon the end of each trunnion pin held in place 95 by a cotter pin 24.

Attached to the beams 20 are upwardly extending supporting irons 25 which extend upward and then inward above the beams 20, then straight upward and are attached to 100 each other by transverse bolts 26 and held spaced from each other by spacer sleeves 27. The upper ends of these irons 25 are engaged with each other by a U-shaped member 28. Mounted between the irons 25 and upon the 105 bearing supported by the means 20 is a grooved wheel 29 beneath which and around which the bight of the cable 16 passes. One end of this cable 16 is attached at any desired point to the beam 10 or any other rela- 110

tively fixed object, and the other end of the cable 16 is connected to a winding drum of any suitable or usual construction (not shown). It will be obvious now that when 5 the cable 16 is unwound from the drum, that the bucket will descend, and that when the cable is wound upon the drum, the cable will ascend.

As before stated, means is provided for 10 closing the doors 18 when the bucket is raised from its discharged point and reaches a predetermined distance from the carrier. A particular means for automatically closing 15 the doors forms the subject matter of my above mentioned Patent #1,406,327, but any suitable means may be used for causing the closing of the doors when the bucket has been raised to a predetermined point with relation to the carrier, this present application having to do entirely with the 20 means whereby the doors are automatically opened when the bucket has been lowered into close proximity to the dump upon which the contents of the bucket are to be 25 discharged.

I have illustrated in this application, as a means for causing the closing of the doors, the mechanism in my pending application above referred to, which mechanism is as 30 follows:—Mounted upon the carrier 10 are two downwardly extending U-shaped members 30, these members being rigidly mounted upon the carrier and extending downward any desired distance. Mounted upon the 35 beams 20 in bearing brackets disposed above these beams are transverse shafts 31. These shafts each carry upon its opposite ends the grooved wheels 32 and adapted to be wound upon these grooved wheels are the cables 33 40 which extend directly downward and pass over the rollers or sheaves 34. These are two cables at each end of the bucket and two sheaves 34 at each end of the bucket. The cables at each end of the bucket pass downward beneath the corresponding sheaves 34 45 and then extend downwardly and laterally and engage the eyes of downwardly and laterally extending rods 36. These rods pass through coiled contractile springs 37. Each 50 of these springs 37 bears at one end against a nut or head on the rod 36 and the other end bears against an angular iron 38 which is operatively connected to the corresponding door, the rod 36 passing out through the angular end of the iron. 55

It will be obvious now that a draft upon the cables 33 will cause the compression of the springs 37 and these, acting through the U-shaped irons 38, will draw the doors to a 60 closed position. Each shaft 31 carries upon it a pinion 39 and this pinion is engaged by a vertically extending rack bar 40. There are two of these rack bars disposed at opposite ends of the beam 20, each of these 65 rack bars being slidingly mounted in a

bracket 41, this bracket 41 constituting means for supporting the corresponding shaft 22 and the bracket holding the rack teeth of the rack bars 40 in engagement with the corresponding pinion 39.

70

It will be obvious now, assuming that the doors are open, that upon the upward movement of the bucket the rack bars 40, which were forced upward by the opening movement of the doors, will eventually strike 75 against the ends of the depending members 20, and as the bucket continues to move upward, the rack bars 40 will be forced downward, thus rotating the winding shafts 32 in a direction to cause the grooved winding 80 wheels or drums 32 to raise the doors to their closed position, where these doors are held by suitable latching devices which form the particular subject matter of this particularly application and which will be now described, it being understood that while I have illustrated a door closing means which forms the subject matter of a pending application for patent filed of even date here-with, yet I do not wish to be limited to this 85 specific door closing means, and the relation with the door latching and releasing means will now be described.

Each door has pivoted to it a pair of link sections 42, which in turn are pivoted by a 90 transverse pivot pin 43 to a pair of link sections 44. These link sections 44 at their extremities are pivotally connected to a supporting bar 45 which extends upward through a slot in the corresponding door 100 and into the bucket, and is attached at its upper end to the bucket, as at 46. There are two of these supporting bars 45 and these bars intersect each other and are fastened at their intersection by a transverse pin 47. 105 Disposed below the bucket are the transversely extending angle irons 48 held in spaced relation to each other by the spacing sleeves 49, and extending through the ends of these angle irons and through the spacing 110 sleeves are the bolts 50. Pivoted on each of these bolts are the actuating members 51, each pair of members being pivoted upon the bolt 43 and extending beyond this pivotal point and being connected by a transverse 115 bolt 52. When the doors are closed, the weight of the transverse bars 48 transmitted through the members 51 acts to shift the links 42 and 44 into a position (see Fig. 3) 120 slightly out of alignment with each other, and the further movement of the links being prevented by the stop bolt 52. When, however, the bars 48 strike the ground or strike the coal heap, the bars 48 move upward, the members 51 will move upward, and the links 125 42 and 44 will break at their point of pivotal connection 43 and fold to thus permit the doors to swing open. The doors may then be closed by the means heretofore stated.

It will be seen that the door holding and 130

releasing means which I have described and illustrated is very simple and that it is automatic in its action so that the coal or other material is discharged upon the dump from 5 a point very closely adjacent the dump so that the coal or other material will not be dropped from a long distance and broken or scattered. So long as the weight of the 10 transverse bars 48 is upon the coupled links 42 and 44, the links cannot break upward at their joints and the downward pressure of the coal on the doors will not open the doors. As soon, however, as the joint between the links has passed a plane intersect- 15 ing the point of pivotal engagement of the links with the flanges on the door, the joint and the point of pivotal engagement of the links 41 with the supporting bar 45, the weight of the material on the doors, as well 20 as the slight upward movement of the bars 48, will cause the links to break and shift to the position shown in full lines in Figure 4, thus permitting the doors to swing vertically downward. The links being upon the 25 outside of the door are carried outward so that the coal or other material will not be discharged upon the links so that there will be no danger of blocking the links and impeding their return movement when the 30 doors are closed. It will be obvious that the bars 48 will form a little impediment to the discharge of coal from the bucket.

The mechanism is simple and has been found thoroughly operative in actual practice.

I claim:—

1. In a material transporting mechanism of the character described, a bucket having a door controlling the discharge of material 40 therefrom, means for raising or lowering the bucket, means for automatically closing the door upon the upward movement of the bucket to a predetermined height, means for latching said door in a closed position, and 45 means acting to unlatch the door to permit the door to swing open when the bucket has descended to a predetermined position.

2. In a material transporting mechanism of the character described, a bucket having 50 a door controlling the discharge of material therefrom, means for raising or lowering the bucket, means automatically closing the door upon the upward movement of the bucket to a predetermined height, and means 55 for latching said door in a closed position, said means depending below the bucket when the door is closed and acting to unlatch the door to permit the door to swing open when the bucket has descended to a 60 predetermined point and the means strikes an impediment.

3. In a transporting mechanism of the character described, a vertically movable bucket having a swinging door controlling 65 its discharge, a member mounted upon the

bucket and vertically movable with relation thereto and operatively connected to the door to cause the closing of the door when the vertically movable member is depressed by striking an impediment, said member 70 being movable upward by an opening of the door, and latching means depending below the bucket and normally holding the door closed but releasing the door to permit the door to swing open upon the contact of 75 said latching means with an obstruction.

4. In a material transporting mechanism, a vertically movable bucket having swinging doors at its bottom, means for closing the doors upon an upward movement of the 80 bucket to a predetermined point, means for holding said doors closed but releasing the doors upon a downward movement of the bucket to a predetermined point comprising 85 door holding members shiftable into holding position when the doors are closed, a releasing member disposed below the doors and common to both of the door holding members and vertically movable with relation to the bucket upon contact with an 90 impediment, and operative connections between said member and said holding members to release the holding members upon a relative movement of the releasing member and the bucket. 95

5. In a material transporting mechanism, a vertically movable bucket having swinging doors at its bottom, means for closing the doors upon an upward movement of the bucket to a predetermined point, and means 100 for holding said doors closed but releasing the doors upon a downward movement of the bucket to a predetermined point comprising a pair of door holding links for each door, the links of each pair being pivoted to each other, one of said links of each pair being pivoted to the door, a support to which the outer end of the other link is pivoted, a bar disposed below the bucket and movable in a vertical plane with relation 105 thereto, connecting members operatively connecting said bar to the jointed extremities of said first named links, and a stop mounted upon each connecting member and bearing upon one of said links and limiting 110 the movement of said links in one direction with relation to each other. 115

6. In a material transporting mechanism, a vertically movable bucket having swinging doors at its bottom, means for closing the 120 doors upon an upward movement of the bucket to a predetermined point, and means for holding said doors closed but releasing the doors upon a downward movement of the bucket to a predetermined point comprising a pair of door holding links for each door, the links of each pair being pivoted to each other, one of said links of each pair being pivoted to the door, a supporting member for each link attached to the bucket 125 130

and extending downward and to which the outer end of the outermost link is pivoted, a transverse bar disposed below the doors, members pivoted to the ends of the transverse bar and normally extending upward and inward and pivoted each to the corresponding pairs of links at the pivotal joint between the same, said members extending beyond said pivotal joint and being provided with stops engaging the innermost link of the pair and limiting the movement of said links in one direction.

7. A transporting mechanism of the character described including a vertically movable bucket having a pair of hinged doors at its lower end, downwardly and outwardly curved supporting bars attached on the interior of the bucket crossing each other and extending to the exterior of the doors, the doors being slotted for the passage of said bars, two pairs of links for each door pivoted to each other, one pair of links being pivoted to the door, the other pair of links being pivoted at its outer end to the supporting bar, means

urging said links in one direction slightly beyond an aligned position and adapted when the bucket is lowered to a predetermined position to shift said links into alignment and beyond the position of alignment whereby said links will break at the joint between the links and permit the door to swing outward, and means limiting the movement of the links in the reverse direction to a point slightly beyond the position of alignment.

8. In a material transporting mechanism, a vertically movable bucket having a swinging door at its bottom, means for raising or lowering the bucket, means for latching the door in a closed position, and means for releasing said latching means comprising a member disposed beneath the door and extending at right angles to the vertical axis of the bucket and intersecting the vertical axis of the bucket, said member having operative connections to the latching means.

In testimony whereof I affix my signature.

FRANKLIN E. ARNDT.
